REFRIGERATING APPARATUS

Sylvester M. Schweller, Dayton, Ohio, and Ernest H. Schilling, La Fayette, Ind.; said Schilling assignor to Peerless Wire Goods Co., Inc., La Fayette, Ind., a corporation of Indiana, and said Schweller assignor to General Motors Corporation, Dayton, Ohio, a corporation of Delaware

Application September 28, 1935, Serial No. 42,654

1 Claim. (Cl. 211—153)

This invention relates to improvements in the construction of refrigerator cabinets and more particularly to the construction and method of making food supporting shelves employed in the 5 interior thereof.

It is an object of our invention to provide an improved type of shelf for supporting articles to be cooled in position in refrigerator cabinets and to provide a novel method of making same.

10 Another object of the invention is to provide a shelf which will have a neat and finished appearance as viewed from the front of a refrigerator cabinet when the food compartment access door thereof is open.

15 With the foregoing objects in view it is to be understood that the shelf must be constructed so as not to interfere with the circulation of air within the refrigerator, to provide a flat or plane surface to objects placed thereupon and to be 20 constructed so as to support small containers and the like without upsetting same thereupon.

25 Further objects and advantages of the present invention will be apparent from the following description, reference being had to the accompanying drawings, wherein a preferred form of the present invention is clearly shown.

In the drawings:

Fig. 1 illustrates a front view of a refrigerator cabinet having shelves constructed according to 30 the present invention mounted therein;

Fig. 2 is a top plan view of our improved shelf;

Fig. 3 is an enlarged sectional view taken on the line 3—3 of Fig. 2 and showing in detail the arrangement of cross wires relative to the rim 35 member of the shelf;

Fig. 4 is a fragmentary sectional view taken on the line 4—4 of Fig. 3;

Fig. 5 is a fragmentary sectional view taken on the line 5—5 of Fig. 3;

40 Fig. 6 is a fragmentary sectional view taken on the line 6—6 of Fig. 1 and shows the mounting of the shelf in the refrigerator cabinet;

Fig. 7 is a top plan view of a die or the like member employed for receiving and holding the 45 rim portion of a shelf during the act of performing a certain operation thereon;

Fig. 8 is a view partly in section of an apparatus for punching the rim portion of the shelf;

50 Fig. 9 is a view similar to Fig. 8 showing the apparatus in a position after having completed the punching operation;

Fig. 10 is a sectional view of the punching apparatus taken on the line 10—10 of Fig. 8;

55 Fig. 11 is a fragmentary enlarged top plan view

of the rim portion of a shelf after having been punched according to the invention;

Fig. 12 is a view illustrating a method of welding cross wires to the rim portion of a shelf; and

Fig. 13 is a view illustrating a method of deforming the ends of cross wires of a shelf into substantially the same horizontal plane with the apex of the round rim portion.

Referring to the drawings and particularly to Fig. 1 thereof there is shown a refrigerator cabinet generally represented by the reference character 15. Cabinet 15 comprises a food storage chamber 16 formed by a metal liner having insulation surrounding same. A plurality of metal panels or a metal shell 17 is placed over the insulating material which surrounds the food storage chamber 16 and this shell forms the exterior finished walls of the cabinet and provides a support for the chamber and insulation. The storage chamber 16 is divided into a plurality of 10 15 superimposed compartments by a plurality of shelves generally represented by the reference character 18. Shelves 18 may be supported within the chamber 16 in any suitable and well-known manner and are herein disclosed as being mounted upon pegs 19 (see Fig. 6) secured to and extending inwardly from opposed side walls of chamber 16. It will be noted that the shelf supporting pegs 19 located at the rear of chamber 16 are disposed on a somewhat lower horizontal 20 25 plane than the pegs at the front of chamber 16 for a purpose to be hereinafter described. A door 20 forms a closure member for the opening which affords access to chamber 16.

Each shelf 18 comprises a heavy wire rim member 21 which is round in cross-section and formed into a general rectangular frame design as shown in Fig. 2 of the drawings. The rim member 21 of shelf 18 is in the present disclosure approximately five-sixteenth inch in diameter and is 30 35 40 formed from a straight piece of wire bent into the shape disclosed and has its ends welded or otherwise firmly secured together. A plurality of horizontally spaced apart cross wires 22 of approximately one-eighth inch diameter extend 45 from the front to the back of shelf 18 parallel to one another and are secured to the rim member 21. It will be noted (see Figs. 3 and 4) that all portions of the rim member 21 of shelf 18 lie in the same horizontal plane and that the ends of wires 22 at the rear of the shelf lie upon the top of rim member 21 and are secured thereto in any suitable manner such as by spot-welding the same thereto. The opposite ends of cross wires 22 disposed at the front of shelf 18 fit into slots 50 55 60 65 70 75 80 85 90 95 100 105 110 115 120 125 130 135 140 145 150 155 160 165 170 175 180 185 190 195 200 24 provided in the material of rim 21 in a manner to be hereinafter more fully described. The front ends of wires 22 are welded or otherwise secured within the slots 24 and the tops thereof are substantially flush with or have the apex at the top thereof disposed in substantially the same horizontal plane with the apex at the top of the round rim 21. It will be seen therefore that the shelf 18 as viewed from the front of cabinet 15, when door 20 is open, has a smooth rounded uniform finished appearance throughout its width. In other words, the front edge of the improved shelf 18 is devoid of spaced apart upwardly extending cross wires similar to the showing in Fig. 5 of the drawings which has heretofore been conventional. It is to be understood that the construction employed along the front edge of the shelf may also be incorporated along the rear edge of shelf 18, if desired. The construction disclosed obviously renders the shelf thicker at its rear portion than at the front thereof and the arrangement of the pegs 19 at the rear of chamber 16, as shown in Fig. 6 of the drawings, on a lower elevation than pegs 19 at the front of the chamber permits the top food supporting surface of shelf 18 to be in a horizontal plane parallel with other horizontally arranged portions of the refrigerator cabinet.

Having described and illustrated the construction of the improved shelf 18 of the present invention one method of making same will now be described by referring to the showing in Figs. 7 to 13 inclusive of the drawings. In Fig. 7 there is disclosed a die or the like member 30 of rectangular form having a substantially semi-cylindrical groove 31 provided in its top surface adapted to receive the wire rim member 21 for performing the operation of punching the spaced apart slots 24 therein. A portion of die 30 along one longitudinal edge of groove 31 is cut away as illustrated at 32 so that the edge of groove 31 along the inner portion of rim 21 is disposed on a lower elevation than the opposite edge of groove 31 for a purpose to be hereinafter more fully described. The die 30, with rim 21 positioned in the groove 31, is placed under a punch-press or the like apparatus as shown in Figs. 8, 9 and 10.

The punch-press apparatus may be of a conventional and well-known type and includes a reciprocating metal block 34 which carries a plurality of hardened metal punch members 35 stationarily secured thereto by bolts or any other suitable means 36. A metal pressure plate 37 is movably carried by the block 34 and is provided with a plurality of openings 38 through which the punch members 35 are adapted to extend. A resilient member 39 constructed of rubber or any other suitable compressible material is carried by block 34 and is disposed between this block 50 and the pressure plate 37. Springs may, if desired, be substituted for the rubber compressible member 39 in the apparatus disclosed. A plurality of rods 40, each having an enlarged head portion 42 which is received in a counter-bore 43 provided in pressure plate 37, are secured in any suitable manner to the reciprocating block 34 for suspendingly carrying the members 35 and 39.

With the wire rim member 21 within groove 31 of block 30 and positioned beneath the punch-press apparatus as shown in Fig. 8, the rim 21 is ready to be operated upon. As the apparatus is manipulated to move block 34 downwardly the plate 37 engages rim member 21, it being understood that plate 37 entirely covers the peripheral

boundaries of rim 21, and further downward movement of block 34 causes plate 37 to apply pressure to the rim 21 to hold same firmly in place in groove 31 and to prevent rotation thereof when the punch members 35 begin to cut into or apply pressure on the one longitudinal side of rim 21. The rubber block or blocks 39 will, of course, be compressed between plate 37 and block 34 during movement of punch members 35 into engagement with rim 21. As the apparatus moves 10 the punch members 35 into the material of rim 21 these punch members 35 cut the slots 24 in the one side of rim 21 or in the material thereof, beginning at approximately the apex at the top of rim 21 and extending inwardly thereof, along 15 the longitudinal portion thereof to be used as the front of the shelf. During the act of cutting the slots 24 the metal of rim member 21 is pushed or caused to flow outwardly as at 47 away from the bottoms of punch members 35 into the space 20 provided by the cut-away portion 32 in the die 30 (see Fig. 9). The edge of groove 31 adjacent the cut-away portion 32 being below the opposite edge of groove 31 and below the point at which the metal of rim 21 tends to flow thereby causes 25 the lower edge of groove 31 to grip the rim member 21 and prevent that portion thereof being operated on from turning while pressure is being applied by plate 37 to all other portions of the rim member. Other methods of cutting the slots 30 24 in rim member 21 may be employed but the present method is preferable because the flow of metal to form the extrusions 47 as described provides a greater supporting and welding surface 35 area for the cross rods 22 upon or within the rim 21. After the punching operation has been completed as illustrated in Fig. 9 of the drawings the rim member 21 is then ready to have the cross wires 22 applied thereto or mounted thereon. The design of the slots 24 provided or cut in rim member 21 may best be seen by reference to Fig. 11 of the drawings.

A cross wire 22 is placed in each of the horizontally spaced apart slots 24 of rim member 21. 45 Either end of these cross-rod wires 22 may have been made fast to the rim 21. However, after the cross wires 22 have been positioned within slots 24 to form the food supporting surface of the shelf 18, the shelf is then placed between two electrodes 51 and 52 of a welding apparatus so that the one of the electrodes 52 will engage the top of the end of cross wire 22 while the other electrode 51 engages the lower portion of the rim member 21 as shown for illustration purposes in Fig. 12 of the 55 drawings. The heat passing between electrodes 51 and 52 through the end of cross-rod 22 and rim or frame 21 causes the cross-rods and rim 21 to be firmly bonded or fused together. It will be noted that the apex or top portions of cross 60 wires 22 are, when positioned in slots 24, spaced a distance of approximately $\frac{1}{2}$ inch from the apex or top of rim 21. This spacing is for the purpose of preventing heating of rim 21 only and for insuring that heat will be simultaneously transmitted through the end portions of the cross wires 22 and the rim 21 for causing bonding thereof together. After the cross wires 22 have been bonded to rim 21 by the welding operation the shelf is then placed beneath a press (see Fig. 13) and a 70 punching or pressing tool 53 is caused to strike the end of each of the wires 22 to slightly deform same to cause the distance between the tops of cross wires 22 and the top of rim member 21 to be diminished or eliminated so that the top surfaces 75

of wires 22 will be substantially flush with or on the same level as the top surface of rim 21.

After the shelf has been constructed by the method above described it may be plated in any suitable and conventional manner with any desired metallic substance such for example, as tin or chromium to provide a finish coat over the shelf which will resist or prevent rusting of the metal and which will improve the appearance of the shelf 18. It will be understood that the plating of shelf 18 will cause all crevices, etc. at the joints in the shelf structure to be filled with the plating material to thus provide smooth surfaces adjacent joints of wires 22 with rim 21 so as to render the shelf easily cleanable.

From the foregoing it will be seen that we have provided an improved shelf for refrigerator cabinets and that we have provided a novel method of making the improved shelf. The improved shelf is of neat appearance since the front edge thereof is smooth and unobstructed by protruding or upstanding ends of cross wires or by portions of a lattice-work as is common in present-day shelf structures. The improved shelf inherently 25 seals the metal which flows from the slots provided in the rim portion 21 since the bosses or extrusions 47 are on the inner surface of rim 21 where they are not seen from the front of the refrigerator cabinet. Our improved shelf has 30 utility in that by eliminating the protruding ends of lattice-work or the ends of cross wires at the top of the front edge thereof any object striking the front edge of the shelf during the act of placing same in the food chamber of the refrigerator cabinet will readily slide over the smooth rounded edge and upon the food supporting surface thereof provided by the cross wires. Our im-

proved shelf, by virtue of the method of attaching the cross wires to the heavy rim member, provides a shelf of great rigidity and eliminates the necessity of providing a centrally located reinforcing cross piece.

While the form of embodiment of the invention as herein disclosed, constitutes a preferred form, it is to be understood that other forms might be adopted, all coming within the scope of the claim which follows.

What is claimed is as follows:

A shelf for a refrigerator cabinet including a bounding rim and a plurality of spaced apart cross members connected to opposite sides of the rim, said rim being solid and forming the sole support of said cross members, at least one of said sides of said solid bounding rim being deformed at a plurality of spaced apart points to provide notches therein, the deformations in said rim being of such character as to extend the notches from the top of said one side of said bounding rim inwardly toward the opposite side thereof and from a point inwardly of the outer edge of said one side of said rim toward the bottom thereof to form a continuous end wall surface and a relatively long continuous bottom wall surface for said notches, each of said notches receiving and supporting one end of each cross member within a portion of the horizontal plane occupied by said bounding rim, and the bottom wall surface of said notches being spaced a predetermined distance from the top of said rim to position the top of each cross member at said one side of said rim on substantially the same level with the top of said bounding rim.

SYLVESTER M. SCHWELLER.

ERNEST H. SCHILLING.
